SAFETY BURNER

Horace L. Hirschler, San Francisco, Calif.

Application April 15, 1932, Serial No. 605,515

2 Claims. (Cl. 158—117.1)

My invention relates primarily to burners for use with gas and is especially concerned with the mechanism adapted to be used with gas for the safe combustion of such fuel.

5 An object of my invention is in general to improve gas burning and controlling mechanism.

Another object of my invention is to provide a gas burner particularly adapted for safe use with a water heater.

10 An additional object of my invention is to provide a gas burner provided with a pilot light and having means for disabling the main burner and the pilot burner in the event of gas failure.

A further object of my invention is to provide 15 means for preventing the operation of the pilot burner under adverse conditions.

The foregoing and other objects are attained in the embodiment of the invention shown in the drawing, in which

20 Figure 1 is a cross section on a median plane of a safety burner constructed in accordance with my invention.

Figure 2 is a cross section, the plane of which is indicated by the line 2—2 of Figure 1.

25 Figure 3 is a cross section showing in plan the safety burner of my invention installed in a water heater.

In its preferred form, the safety burner of my invention is inclusive of a hollow body having 30 a main gas inlet and a pilot gas inlet and provided with a main gas burner and a pilot gas burner, there being a main gas valve and a pilot gas valve for controlling communication between the body and the main and pilot burners respectively, together with a thermostat mounted on the body, and adapted to actuate a lever within the hollow body for controlling the operation of the main gas valve and the pilot gas valve.

35 In the form of my invention disclosed in the drawing, there is provided a hollow body 6 which is preferably of cast metal and which is provided with a main gas inlet 7 adapted to be connected to a suitable source of gas. The body 6 is likewise provided with a box 8 which is internally threaded to receive a nipple 9 on which a main gas burner 11 is mounted. This burner comprises the usual Venturi section affording air inlet apertures 12 controlled by a rotatable shutter plate 13 and likewise includes a hollow head 14 with 40 respect to which a top 16 is held in adjustable spaced relationship by a stud 17 threadedly engaging a spider 18 cast integrally with the head 14. A variable annular opening 19 is thus provided for the emission of a gas and air mixture. 45

50 In order that gas flow from the interior 21

of the hollow body 6 to the burner 11 can be controlled, I preferably mount a ball valve 22 to underlie a central passage 23 extending through the nipple 9 and ordinarily urge the ball from its seat by means of a coil spring 24 not only 5 abutting the ball 22 but likewise abutting a burner tip 26 fixed in the end of the nipple 9. To limit the range of movement of the ball 2, the body 6 is provided with a boss 31 through which a stud 32 passes to form an abutment for the ball. 10 A packing gland 33 or other closure prevents the escape of gas from the interior 21 to the atmosphere.

In order that the flame issuing from the burner head 14 can be extinguished and re-ignited as 15 desired, I preferably provide a pilot burner. To this end the body 6 is provided with a pilot gas inlet 34 connected to a suitable source of gas and communicating by means of a passage 36 with an annular passage 38 within a disc 37. The 20 passage 38 extends past a seat 39 to radial openings 41 in a plug 42 likewise provided with a peripheral channel 43. This channel opens onto a bore 44 in an extension 46 of the body 6 and communicates through a small hole 47 with a 25 chamber 48 into which a pilot burner tube 49 is inserted.

Within the tube 49 is a thimble 51 having an aperture 52 therein to provide for the issuance of a jet of gas which mixes with air aspirated 30 thereby through openings 53 in the tube 49. The mixed air and gas passes through the tube 49 and issues from a burner opening 54 adjacent the far end thereof. The flame extending from the opening 54 is in sufficiently close proximity to the opening 19 to ignite the gas and air mixture issuing therefrom whenever such a mixture flows. 35

So that no combustible material may issue from opening 19 in the event the flame from the tube 49 is extinguished, I preferably provide a safety 40 thermostat comprising generally an outer tube 56 which is held in adjusted position within a boss 57 on the body 6 by a jam nut 58. The upper end of the tube 56 is preferably closed by a plate 59 and is surrounded by a shield 61 of high temperature material. Within the tube 56 is a rod 62 having a coefficient of expansion materially different than that of the tube 56, so that upon variations in temperature of the tube 56 and the rod 62 relative movement between them occurs. This relative movement is made use of to control the issuance of combustible from the opening 19. 45

To this end the lower end of the rod 62 is brought approximately to a point and bears upon 50 55

a resilient lever 63 mounted within the hollow interior 21 of the body 6. The lever 63 at one end is provided with a nearly circular but slightly elongated aperture overlying the ball valve 22, 5 and intermediate the ball valve and the point of contact of the rod 62 the lever 63 is offset, as at 64, to provide a bearing against a fulcrum 66. The fulcrum is preferably adjustable and is comprised of a stud 67 screwed into the body 6 and carrying 10 at its inner end an upstanding pin piercing the lever 63 and forming a guide therefor.

Because of this mechanism, when the flame from the opening 54 is extinguished, the thermostat promptly cools and the relative motion between the tube 56 and the rod 62 produced thereby causes the lever 63 to rock on its fulcrum 66 to urge the ball valve 22 into closed position against the inferior urging in the opposite direction of the spring 23. It is therefore impossible for combustible material to issue from the opening 19 if there is no flame at the opening 54.

To interrupt the issuance of combustible from the opening 54 in the event that there is no flame present at that point, I preferably extend the lever 25 63 to overlie and abut a plunger 68 guided within the plug 42 and at its lower end adapted to abut against the seat 39 to prevent flow thereby. Thus when the valve 22 is urged toward closed position, the plunger 68 is likewise urged to closed position 30 and prevents the issuance of combustible from the aperture 54.

In order, however, that combustible can again be caused to issue from the opening 54 for re-ignition and for further operation of the mechanism, I provide means for opening the passage past the seat 39 independently of the thermostat 35 62. To this end there extends into the passage 38 a screw 69 engaging a threaded ring 71 seated in the body 6, and maintaining in compression a packing washer 72 interposed between the ring 71 and the member 37, a packing 73 interposed between the member 37 and the plug 42, as well as a packing washer 74 interposed between the plug 42 and the body 6. The character of these various 45 packing washers is such that leakage from the body 6 is entirely prevented.

The screw 69 is rotated by an elongated lever 76 engaged therewith, so that upon actuation of the lever and consequent rotation of the screw 69, an 50 extension 77 on the screw is urged axially into abutment with the member 68 and dislodges it from its seat 39, thereby permitting gas to flow. This movement by the member 68 is partially resisted by the lever 63, but since this lever is resilient the member 68 can be opened sufficiently to 55 permit a flow of gas to the pilot burner. When the pilot burner has again been ignited, the temperature of the thermostat increases, the pressure against the lever 3 is relieved, and under the urgency of the spring 23 the ball valve 22 is again unseated and the member 68 is again permitted

to remain in open position; thereupon the main burner can again operate normally.

After the mechanism has once been shut down as previously described, the fuel is customarily re-ignited by an attendant and in order that the mechanism will again be conditioned to shut down automatically should the pilot flame for any cause be extinguished, I preferably mount the mechanism as shown in Figure 3. In this environment the entire mechanism is mounted within a housing 81 in which there is an opening 82 through which access to the mechanism can be obtained. A door 83 is designed in one position to close the opening, and is hingedly mounted as at 84 on the housing 81. On the door 83, I preferably provide 15 an elongated extension 86 which, when the door is in open position, is entirely clear of the path of the lever 16, so that the lever can be moved from "run" position away from the member 88 as shown at A in Figure 3, to "start" position as 20 shown at B in Figure 3, wherein the member 88 is held from its seat 39. When, after the pilot light has been re-ignited, the door 83 is again closed, if the lever 16 has not previously been moved from "start" position to "run" position, 25 the extension 86 on the door during the closing movement thereof engages the lever 16 and moves it from "start" position to "run" position, thereby resetting the mechanism for further automatic operation. 30

If desired, the extension 86 can be omitted, in which event the door 83 abuts the end of the lever 16 and cannot be fully closed until the lever is moved to its "run" position. To render the lever especially noticeable it can be provided with an 35 enlarged and preferably brightly colored knob 87.

I claim:

1. A safety burner comprising a hollow body, a main gas burner mounted on said body and receiving gas therefrom, a pilot gas burner, a 40 main valve within said body to control flow to said main burner, a pilot valve within said body to control flow to said pilot burner, a resilient lever within said body operable to actuate said valves, a thermostat on said body responsive to 45 said pilot burner operable to actuate said lever, and means on said body to operate said pilot valve independently of said thermostat.

2. A safety burner comprising a hollow body adapted to be connected to a source of gas, a main 50 gas burner mounted on and receiving gas from said body, a main gas valve to control flow from said body to said main burner, a pilot gas burner mounted on and receiving gas from said body, a pilot gas valve to control flow to said pilot burner, 55 a fulcrum within said body, a resilient lever bearing on said fulcrum and operable to actuate said main valve and said pilot valve, a thermostat mounted on said body and operable to actuate said lever, and means on said body to actuate said pilot valve independently of said thermostat. 60

HORACE L. HIRSCHLER.
